DESIGN FOR A HAND OPERATED GENERATOR FLASHLIGHT

Cornelius S. Nicoud, Highland Park, Ill., assignor
to Nicoud Manufacturing Company, a corpora-
tion of Illinois

Application November 8, 1943, Serial No. 111,628

Term of patent 14 years

To all whom it may concern:

Be it known that I, Cornelius S. Nicoud, a citizen of the United States of America, residing at Highland Park, in the county of Lake and State of Illinois, have invented a new, original, and ornamental Design for Hand Operated Generator Flashlights, of which the following is a specification, reference being had to the accompanying drawing, forming a part thereof, in which:

Figure 1 is a view in side elevation of a hand

operated generator flashlight showing my new design.

Figure 2 is a bottom plan view of the hand operated generator flashlight; and

Figure 3, a top plan view of the hand operated generator flashlight.

I claim:

The ornamental design for a hand operated generator flashlight, as shown.

CORNELIUS S. NICOUD.
